UNITED STATES PATENT OFFICE.

CLAYTON H. LONGENECKER, OF CAMPBELLTOWN, PENNSYLVANIA.

VEHICLE-BRAKE.

SPECIFICATION forming part of Letters Patent No. 795,144, dated July 18, 1905.

Application filed February 14, 1905. Serial No. 245,600.

To all whom it may concern:

Be it known that I, CLAYTON H. LONGENECKER, a citizen of the United States, residing at Campbelltown, in the county of Lebanon 5 and State of Pennsylvania, have invented certain new and useful Improvements in Vehicle-Brakes; and I do hereby declare the following to be a full, clear, and exact description of the invention, such as will enable others skilled in the art to which it appertains to make and use the same.

My invention relates to vehicle-brakes; and it consists in certain improvements in construction which will be fully disclosed in the 15 following specification and claim.

In the accompanying drawings, which form part of this specification, Figure 1 is an inverted plan view of the rear portion of a vehicle, showing my invention applied; and Fig. 20 2 a perspective view of part of the brake mechanism and the rear axle.

Reference being had to the drawings and the designating characters thereon, the numeral 1 indicates the pole or reach of a vehicle; 25 2, the rear axle provided with wheels 3 3'. 4 4' indicate the hounds.

5 indicates a compound lever having arms 6, 7, and 8 and is pivotally secured to the axle 2 by a screw-bolt 9, and to the arm 6 is attached a rod 10, which extends forward and 30 is secured to a lever 11, pivotally attached to the pole 1, by which power is applied to the brakes.

To the arm 7 is pivotally secured a rod 12, 35 which is pivotally secured to one end of a lever 13, and the opposite end of lever 13 is pivotally secured at 15 to the outer end of the brake-lever 16, which is pivotally secured to a plate 17 at 18 and acts as a fulcrum to the 40 brake-lever 16, and to the outer end of lever 16 is attached a brake-shoe 19, concavo-convex in form, and engages the band 20 on the inner end of the hub 21 of the wheel 3.

To the pin 14 is connected a bar 22, which 45 is pivotally connected to the outer end of the brake-lever 23, which is pivotally secured to plate 24 at 25 and is provided with a brake-shoe 26 of the same construction as the shoe 19 and engages the hub-band 20 diametric-

ally opposite shoe 19. The plates 17 and 24 50 extend through and are secured to the axle 2 by a yoke 27 and a clamping-bar 28 and nuts 29 29, which engage the projecting ends 30 30 of the yoke.

To the arm 8 of the compound lever 5 is 55 pivotally secured a rod 12', which is pivotally secured to one end of a lever 13', and the opposite end of lever 13' is pivotally secured at 15' to the outer end of the brake-lever 16', which is pivotally secured to a plate corresponding 60 with plate 17 at 18' and acts as a fulcrum to the brake-lever 16', and to the outer end of the brake-lever 16' is attached a brake-shoe 19', concavo-convex in form, and engages the band 20' on the inner end of the 65 hub 21' of the wheel 3'.

To the pin 14' is connected a bar 22', which is pivotally connected to the outer end of the brake-lever 23', which is pivotally secured to a plate corresponding with plate 24 at 25' and 70 70' is provided with a brake-shoe 26' of the same construction as the shoe 19' and engages the hub-band 20', diametrically opposite shoe 19'.

The brake-levers are secured to the axle by means corresponding with the plates 17 and 75 24 and are secured to the axle 2 by a like yoke 27 and a clamping-bar 28' and nuts 29' 29', which engage the projecting ends 30' 30' of the yoke.

The mechanism on each side of the center 80 of the axle is a duplicate of that on the opposite side, and each brake-shoe is provided with a leather lining or rubber 31.

It is obvious that the more power employed to operate the lever 11 the tighter and harder 85 the brake-shoes will grip the sand-bands.

This class of brake is especially adapted to light vehicles, and particularly to rubber-tired vehicles, where one object is to save the wear and tear on the tires and another is to get an 90 even and uniform pressure of the brake on both wheels at the same time, and thereby bring the vehicle to a stop or, at least, reduce its speed. It is also obvious that all of the parts of this brake may be made of steel or 95 wrought-iron and can be carried in stock and the parts, when necessary, replaced with little or no trouble.

Having thus fully described my invention, what I claim is—

A vehicle-brake comprising a triple-armed horizontal lever pivotally secured to the axle, 5 brake-shoes engaging opposite sides of the hub of the wheel, levers supporting said brake-shoes and fulcrumed on plates secured to the axle, means for connecting the free ends of said levers, a pivoted connection between said

levers and the triple-armed lever, and a connection between the triple-armed lever and the operating-lever.

In testimony whereof I affix my signature in presence of two witnesses.

CLAYTON H. LONGENECKER.
